(57) **CLAIM**

The ornamental design for a beverage container cap with handle and integrated hole cover, as shown and described.

DESCRIPTION

FIG. 1 is an upper perspective view of a beverage container cap with handle and integrated hole cover in closed position with the drinking hole covered by the handle.

FIG. 2 is a front view of a beverage container cap with handle and integrated hole cover in closed position.

FIG. 3 is a rear view of a beverage container cap with handle and integrated hole cover in closed position.

FIG. 4 is a right side view, of which the left side view is a mirror image, of a beverage container cap with handle and integrated hole cover in closed position.

FIG. 5 is a top view of a beverage container cap with handle and integrated hole cover in closed position.

FIG. 6 is a bottom view of a beverage container cap with handle and integrated hole cover in closed position.

FIG. 7 is an upper perspective view of a beverage container cap with handle and integrated hole cover in carrying position.

FIG. 8 is a front view of a beverage container cap with handle and integrated hole cover in carrying position.

FIG. 9 is a rear view of a beverage container cap with handle and integrated hole cover in carrying position.

FIG. 10 is a right side view, of which the left side view is a mirror image, of a beverage container cap with handle and integrated hole cover in carrying position.

FIG. 11 is a top view of a beverage container cap with handle and integrated hole cover in carrying position.

FIG. 12 is a bottom view of a beverage container cap with handle and integrated hole cover in carrying position.

FIG. 13 is an upper perspective view of a beverage container cap with handle and integrated hole cover in drinking position with the drinking hole exposed.

FIG. 14 is a front view of a beverage container cap with handle and integrated hole cover in drinking position.

FIG. 15 is a rear view of a beverage container cap with handle and integrated hole cover in drinking position.

FIG. 16 is a right side view, of which the left side view is a mirror image, of a beverage container cap with handle and integrated hole cover in drinking position.

FIG. 17 is a top view of a beverage container cap with handle and integrated hole cover in drinking position; and, FIG. 18 is a bottom view of a beverage container cap with handle and integrated hole cover in drinking position.

Any broken line showing is for environmental purposes only and forms no part of the claimed design.
